(57) **CLAIM**

I claim the ornamental design for an EKG viewing tool, as shown and described.

DESCRIPTION

FIG. 1 is a front perspective view of the claimed design; FIG. 2 is a rear perspective view of the claimed design of FIG. 1;

FIG. 3 is a front view of the claimed design of FIG. 1; FIG. 4 is a rear view of the claimed design of FIG. 1; FIG. 5 is a top view of the claimed design of FIG. 1; FIG. 6 is a bottom view of the claimed design of FIG. 1; FIG. 7 is a right side view of the claimed design of FIG. 1; and,

FIG. 8 is a left side view of the claimed design of FIG. 1. The ornamental design which is claimed is shown in solid lines in the drawings.

The broken lines shown in the figures represent portions of the EKG viewing tool that form no part of the claimed design.

1 Claim, 6 Drawing Sheets
